PILE OF T-RAILS AND METHOD OF
BUILDING ITDoré W. Grazier, Johnstown, Pa., assignor to
United States Steel Company, a corporation of
New Jersey

Application February 23, 1950, Serial No. 145,643

4 Claims. (Cl. 214—10.5)

1

This invention relates to a method of piling T-rails for storage and the resulting pile.

Many users of T-rails find it desirable or necessary to maintain a considerable stock thereof on hand. The disposition of any substantial quantity of rails presents quite a problem for numerous reasons. Rails are ordinarily piled by laying them side-by-side, standing on their flanges, one course on another, with wooden spacer strips between courses. This dunnage is of little or no value after one use and represents a substantial item of cost. The resulting piles lack stability unless great care is exercised in their building and have a low space factor which limits the capacity of a storage bed of a given ground area. Sometimes alternate rails in each course are inverted to increase the space factor.

Outdoor unprotected storage of rails is almost the universal rule. This results in weathering and the problem is to reduce deterioration as much as possible. Heretofore, it has been the practice to spray asphalt paint on the exposed ends and tops of the rails for protection against the weather. This paint is objectionable when the rails have to be machined preparatory to use, because it accumulates on the tools and necessitates frequent cleaning thereof. It also introduces a hazard when a rail has to be bent, because the paint tends to cause slippage of spacer blocks used in this operation. A further hazard is the possibility of slippage of tongs or slings used in handling rails.

I have invented a novel method of piling rails which overcomes the aforementioned difficulties and provides a stable secure pile having a high space factor, without the use of spacer strips or other dunnage. Generally speaking, my improved method contemplates piling rails side-by-side in successive courses with their webs at about 45° to the vertical, each rail leaning on the adjacent rail. The rails in alternate courses are disposed with their heads down and the remaining rails have their heads up with their flanges bearing on those of the downturned rails.

A complete understanding of the invention may be obtained from the following detailed explanation which refers to the accompanying drawing, the single figure of which is an end elevation of a pile of rails built up according to the invention.

Referring in detail to the drawing, the pile of rails there illustrated is disposed transversely on two or more spaced supports or sleepers *s* which may be rails, timbers or masses of concrete. The sleepers are substantially horizontal but there is

2

a slight difference in elevation between each sleeper and the adjacent ones to provide a slope or pitch to the rails piled thereon for the purpose of drainage.

In building the pile shown in the drawings, I lay a plurality of rails 10, 11, 12 and 13, etc., side-by-side in close-order relation on the sleepers *s* to form a first course. The rails of the first course are laid with their heads *a* disposed downwardly. The first rail 10 is actually laid on its side and each succeeding rail is laid with the outer edge of its flange *b* engaging the web *c* of the rail previously laid. Thus each rail in the course except the first has its web disposed at an angle of about 45° to the vertical. The flange of each rail after the second, i. e., rails 12, 13, etc., preferably engages the web of the previously laid rail adjacent the head thereof.

When the first course of rails has been laid to the desired width (there is no limit to the width of the pile aside from practical considerations), a second course of rails 21, 22, 23, etc., is laid thereon. The rails of the second course are laid with their heads up and with their flanges bearing on the up-turned flanges of the rails of the first course. The webs of the rails in the second course, furthermore, engage the upper edges of the flanges of the rails in the first course. As a result, the rails of the first two courses, except the first two rails of the first course (10 and 11), are disposed in pairs with their webs parallel and at an oblique angle to the vertical, their flanges congruent, i. e., in flatwise surface contact with the edges thereof substantially flush. One of the under surfaces of the head of each rail in the second course engages the exposed upper edge of the flange of the rail previously laid which is the reverse of the relation of the flanges and heads of the rails in the first course.

When the second course of rails has been laid, a third course of rails 31, 32, 33, etc., is laid thereon with the heads of the rails down and abutting the heads of the rails in the second course. The webs of the rails 31, 32, 33, etc., as a result, engage the sides of the heads of the rails 21, 22, 23, etc. The rails of the third course are related to each other in the same manner as the rails of the first course and afford surfaces for receiving the fourth course of rails 41, 42 and 43 in the same manner that the rails of the second course are disposed on those of the first course. That is to say, each pair of courses after the second repeats the pattern established by the first two courses.

55 A pile of rails built according to my invention

may be laid up to any desired height and any width within practical limits. By reason of the interlocking engagement of the rails of each course and the rails of adjacent courses as explained above, the pile remains rigid and stable regardless of its overall dimensions. The left-hand side of the pile as shown in the drawings is substantially vertical while the right-hand side slopes inwardly since the width of the courses is decreased by one rail for each pair of courses. To prevent the rails at righthand side of the pile from slipping out of place during the piling operation, a wedge 50 is preferably inserted temporarily in the space between the flanges of the last rail laid in the even-numbered courses and the down-turned head of the last rail laid in the odd-numbered courses, although this is not absolutely necessary.

The interfitting arrangement of inclined pairs of rails in any three adjacent courses results in a space factor much higher than the conventional method of piling. In fact, the capacity of a pile of given height covering a given area is practically doubled by my invention. This permits dual piling and use rotation of piles when desired. Since the laying of each course automatically provides spaces for receiving the rails of the next course in stable relation thereto, little or no skill is required on the part of the rail-handling crew. No spacer strips are required and dunnage is eliminated except for the wedges 50, if used. The disposition of all rail surfaces at oblique angles causes rain water or condensation to descend promptly into the valleys and the pitch of the several sleepers causes rapid drainage longitudinally of the pile. The top course of rails forms a roof which is practically watertight. This fact together with the arrangement of all rails in an oblique position and the longitudinal pitch makes it unnecessary to spray the tops and ends of the rail with protective paint. The spaces between adjacent courses are sufficient to permit good ventilation, thereby assuring evaporation of condensation or other moisture which may collect therein. The pile of my invention also facilitates taking inventory since each course of rails provides a predetermined number of spaces for rails of the next course.

I claim:

1. In a method of building a pile of T-rails, the steps including laying a first course of rails side-by-side with their heads disposed downwardly and bearing on a support and one edge of the flange of each rail in said course engaging the exposed side of the web of the adjacent rail, thereby causing the webs of the rails to make an oblique angle with the horizontal, laying a second course of rails on said first course with their webs inclined at said angle to the horizontal and their flanges bearing on those of the rails of the first course, then laying a third course of rails on said second course with their webs inclined

at said angle to the horizontal and the tops of their heads disposed downwardly and engaging those of the rails in the second course in partly overlapping relation.

- 5 2. In a method of building a pile of T-rails, the steps including laying a rail on its side on a support, laying additional rails on said support with their heads down and one edge of their flanges engaging the exposed side of the web of the previously laid rail to form a first course all the rails of which have their webs inclined to the horizontal, laying a second course of rails with their webs inclined to the horizontal and their flanges bearing on those of the rails of the first course, then laying a third course of rails on said second course with their webs inclined to the horizontal and the tops of their heads disposed downwardly and engaging those of the rails in the second course in partly overlapping relation.
- 10 20 3. A pile of T-rails composed of a plurality of courses laid one on the other, each course including a plurality of rails laid side-by-side in close-order relation, the rails of the first course being laid with their webs inclined to the horizontal, their heads down and one edge of the flange of each rail resting on the exposed side of the web of the adjacent rail, the rails of the second course being disposed with their webs inclined to the horizontal and the bottoms of their flanges congruent with those of the rails of the first course, and the rails of the third course being disposed with their webs inclined to the horizontal and the tops of their heads abutting those 35 of the rails of the second course in partly overlapping relation.
4. A pile of T-rails comprising a plurality of courses each composed of a plurality of rails all disposed in inclined positions and in close-order 40 side-by-side relation, each rail leaning on the adjacent rail in the same course, the rails being disposed with their heads downwardly in one course and upwardly in the adjacent course, the flanges of the rails in any course engaging the webs of the rails in an adjacent course, the heads of the rails in any particular course abutting the heads of the rails in one adjacent course and the flanges of the rails in said particular course abutting the flanges of the rails in the other 45 50 adjacent course.
